FOREIGN PATENT DOCUMENTS

EP	2447012	5/2022
GB	2447012	12/2011

Primary Examiner — Keli L Hill*Assistant Examiner* — Harold E Blackwell, II(74) *Attorney, Agent, or Firm* — Hovey Williams LLP(57) **CLAIM**

The ornamental design for a auger and socket holder, as shown and described.

DESCRIPTION

FIG. 1 is a top, front perspective view of an auger and socket holder according to my new design;

FIG. 2 is a top, rear perspective view thereof;

FIG. 3 is a front elevation view thereof;

FIG. 4 is a left side elevation view thereof;

FIG. 5 is a right side elevation view thereof;

FIG. 6 is a rear elevation view thereof;

FIG. 7 is a top plan view thereof; and,

FIG. 8 is a bottom plan view thereof.

The broken lines in the drawings depict portions of the auger and socket holder and form no part of the claimed design.

1 Claim, 7 Drawing Sheets(56)
